SHEET STRETCH BENDER WITH SLIDE
ON MAIN CARRIAGE

Lee B. Green, Lakewood, Ohio

Application November 29, 1952, Serial No. 323,257

12 Claims. (Cl. 153—48)

1

This invention relates to stretch bending machines of the kind which operate to produce a combined stretching and bending operation on a metal sheet or other workpiece.

This application is a continuation-in-part of original application Serial No. 305,377, filed August 20, 1952.

In that original application, there is disclosed a stretch bending machine in which carriages having work gripping units thereon are movable along guideways provided on a pair of longitudinally aligned end frame members. Such end frame members extend in substantially opposite directions away from a die punch located therebetween and which punch is movable to engage and apply a bending force to an intermediate portion of a workpiece extending thereacross while end portions of the workpiece are gripped by the gripping units.

The carriages are moved along the guideways of the frame by suitably driven lead screws and the movement thus imparted to the carriages serves to bring the gripping units into position to engage the ends of the workpiece and also to produce the stretching force which is applied to the ends of the workpiece through the gripping units. Movement of the gripping units by such a lead screw actuation of the carriages has certain limitations and disadvantages, one of which is that the movement imparted to the carriages by the lead screws is relatively slow.

It is, therefore, an object of this invention to provide an improved metal working machine of the above-mentioned stretch bending type having carriage means movable along guide means of a frame and in which work gripping means is carried by slide means operating on guide means of the carriage means.

Another object is to provide a novel stretch bending machine, or the like, in which the carriage or carriages have transversely spaced guideways thereon and the slide means carrying the work gripping means includes block members movable along such guideways.

Still another object is to provide a novel stretch bending machine in which the slide means is confined for substantially parallel movement on the carriage means by alignment control gearing on the meshed rack and pinion type connected between the slide means and the carriage means.

A further object is to provide a new stretch bender of the character mentioned, in which the slide means includes a transverse shaft journaled in the block members and having the rack engaging pinions fixed thereon.

2

Yet another object is to provide a novel stretch bender of the kind above referred to, in which the work gripping means is carried by a rocker means mounted on the transverse shaft between the block members.

It is also an object of this invention to provide a novel stretch bender of the character above indicated, in which power cylinder means mounted on the carriage is connected with the block members for imparting movement to the slide means, and in which other power cylinder means mounted on the carriage is connected with the rocker means for causing rocking of the latter.

The invention can be further briefly summarized as consisting in certain novel combinations and arrangements of parts hereinafter described and particularly set out in the claims hereof.

In the accompanying sheets of drawings, forming a part hereof:

20 Fig. 1 is a partial front elevation of a stretch bending machine embodying this invention;

Fig. 2 is an end elevation of the machine showing the same with portions thereof broken away; and

25 Fig. 3 is a fragmentary elevational view corresponding with a portion of Fig. 1, but showing the same on a larger scale.

As shown in the drawings, the novel stretch bender 10 comprises in general a main frame 11, a pair of pulling units 12 and 13 movable on the frame and adapted to apply a stretching force to opposite ends of a workpiece 14, and a die punch 15 movable to engage an intermediate portion of the workpiece for applying a bending force thereto.

30 The frame 11 comprises an intermediate frame member 16 and a pair of substantially longitudinally aligned end frame members 17 and 18 which have their adjacent ends connected with the intermediate frame member and extend in substantially opposite directions away from the die punch 15. The die punch 15 has a convexly curved die surface 15^a which includes rounded side portions 15^b. The die punch 15 is suitably supported and guided in the intermediate member 16 and is adapted to be moved into engagement with the workpiece 14, in this case by a substantially vertical movement, by the operation of one or more power cylinder devices 19.

35 The end frame members 17 and 18 and the pulling units 12 and 13 supported thereon, are substantially identical for opposite ends of the machine 10 and, hence, only the frame member 17 and the pulling unit 12 need be described in detail.

40 The pulling unit 12 comprises, in general, a

carriage 20 having a slide means 21 thereon, and a rocker means 22 rockably supported by such slide means and forming a support or carrier for a work gripping unit 23. The pulling unit 12 also comprises a grip head 24 forming a part of the gripping unit 23 and engageable with the workpiece 14 and through which head a stretching force is applied to the workpiece. Additionally, the pulling unit 12 comprises transversely spaced power cylinder devices 25, 26 mounted on the carriage 20 and operable to impart movement to the slide means 21, and a second pair of power cylinder devices 27, 28 also mounted on the carriage 20 and operable to impart rocking movement to the rocker means 22.

The end frame member 17 is provided with longitudinally extending transversely spaced front and rear guide portions 29 and 30 forming a guideway 31 along which the carriage 20 of the pulling unit 12 is movable. The frame member 17 is also provided with hold-down guide members 32 and 33 with which guide followers 34 and 35, formed as depending brackets of the carriage 20, slidably cooperate. A suitable actuating means for the carriage 20 is also provided on the frame member 17 and is here shown as comprising a pair of lead screws 36 which cooperate with nuts 37 and are driven by an electric motor 38, or the like, through reduction gearings 39.

The carriage 20 is a suitably shaped rigid structure which includes upright side members 40 and 41, and a transverse bottom wall 42 connecting such side members and having guide followers 43 and 44 thereon which are slideable on the guide members 29 and 30 of the guideway 31. The carriage 20 also comprises a pair of longitudinally extending guideway members or adapters 45 and 46 which are located inwardly of and against the side members 40 and 41 and are bolted, or otherwise suitably secured, to the body of the carriage. The adapters 45 and 46 have longitudinally extending guideway openings therein which provide the carriage 20 with a pair of transversely spaced longitudinal guideways 47. The guideways 47 are located above the main guideway 31 of the frame member 17 and extend in the same direction, that is to say, in a direction away from the die punch 15.

The slide means 21 comprises a pair of transversely spaced block members 49 which are slidably mounted in the guideways 47 of the carriage 20, and a transversely extending shaft 51 extending between and mounted in the block members 49. The shaft 51 is mounted in the block members 49 by having reduced portions 52 journaled in bushings 53, which extend through the block members 49 transversely thereof. The slide means 21 is movable in the guideways 47 and relative to the die punch 15 by the power cylinder devices 25 and 26 of the carriage 20. These power cylinder devices have the cylinders thereof suitably mounted on the carriage 20 and have their piston rods 25a and 26a connected with the block members 49 as by means of the threaded engagement 54.

The rocker means 22 comprises a pair of transversely spaced side members or brackets 55 and 56 and a connecting sleeve 57. The side members 55 and 56 are here shown as being in the form of substantially triangular metal plates which are welded, or otherwise rigidly secured, to the ends of the connecting sleeve 57. The triangular side members 55 and 56 are disposed with one apex or corner thereof directed downwardly, and such lower corners or apices are pro-

vided with mounting bearings which are here shown as being in the form of bushings 58 located in the outer ends of the sleeve 57. The shaft 51 extends through the connecting sleeve 57 and is provided with journal portions 59 on which the bearings 58 are mounted for rockably supporting the rocker means 22 on this shaft between the block members 49.

The side members 55 and 56 of the rocker means 22 are provided, at the upper corners thereof which are nearest the workpiece 14, with bearings 60 and 61 in which the gripping unit 23 is pivotally mounted, and at the other upper corners thereof which are more remote from the workpiece, these side members are provided with bearings 62. The gripping unit 23 is provided with projecting trunnions 64 and 65 which are journaled in the bearings 60 and 61 and mount the gripping unit for swinging movement in the rocker means 22 between the spaced side members 55 and 56 of the latter.

The rocker means 22 is rockable toward and away from the die punch 15 by the swinging movements of the rocker means about the axis of the transverse shaft 51 when such swinging movements are imparted to the rocker means by the cylinder devices 27 and 28. These cylinder devices are pivotally mounted on the carriage 20 by having pairs of trunnions 66 journaled in pairs of bearings 67 and 68 provided on the carriage. The cylinder devices 27 and 28 have their piston rods 69 connected with the side members 55 and 56 of the rocker means 22 by means of the yokes 63 and pivot pins 70 which extend through and are journaled in the bearings 62. The cylinder devices 25 and 26 for actuating the slide means 21 and the cylinder devices 27 and 28 for actuating the rocker means 22, are all double acting cylinder devices.

Further in accordance with the present invention, the slide means 21 is confined for substantially parallel translatory movement in the guideways 47 so as to prevent skewing or misalignment of the slide means relative to the carriage 20 or misalignment of the gripping unit 23 relative to the workpiece or die punch. For this purpose, an alignment control means is provided which interconnects the slide means 21 with the carriage 20. This alignment control means comprises meshing rack and pinion elements 71 and 72 of which the racks 71 are here shown as being secured to the side members 40 and 41 of the carriage 20 as by means of the screws 73.

The pinions 72 are fixed on the shaft 51, as by being mounted on and keyed to reduced end portions 74 which project beyond the block members 49. The racks 71 are located adjacent the guideways 47 of the carriage, such that during movement of the slide means 21 in these guideways by the power cylinder devices 25 and 26, the pinion 72 will roll along the racks. Since the pinions are connected with each other through the shaft 51, the cooperation of the pinions with the racks will prevent skewing of the slide means 21 by confining the same to substantially parallel movements in the guideways 47 of the carriage 20.

By mounting the gripping units 23 on their associated slide means 21 instead of directly on the main carriages 20, the gripping units can be rapidly moved toward or away from the die punch 15 for engaging or releasing the grip heads 24 with the ends of the successive workpieces 14 when the latter are placed in the machine for

the performance of the desired stretch bending operations thereon. The relatively slower movement of the carriages 20 can be used as an initial adjustment of the machine for locating the carriages relative to the die punch 15 to suit the length of workpiece on which the machine is to operate and for subsequently adjusting the setting of the machine when other lengths of workpieces are to be accommodated therein.

When the gripping units 23 are mounted on the carriages 20 by providing the latter with the slide means 24, it is also possible to make use of the power cylinder devices 25 and 26 for assisting the power cylinder devices 27 and 28 in applying the stretching force to the workpiece. The movement of the slide means 24 on the carriage 20 as provided by the power cylinder devices 25 and 26, can be accomplished with very little wear on the relatively movable parts, thus minimizing the frequency with which the carriages are required to be moved by the lead screws 33 and the resulting wear occurring on such lead screws and the nuts 37 cooperating therewith. The present invention, therefore, provides a stretch bending machine having greater operating speed, flexibility and range of usefulness, as well as a machine which is capable of smoother and more accurate performance throughout a long period of life.

The movements of the gripping units 23 and their associated rocker means 22 during the stretch bending operation performed on the workpiece 14, are described in greater detail in the above-identified original application. For the purpose of the present disclosure, it is sufficient to explain that during the stretch bending operation the die punch 15 is moved upwardly to impart a bending force to the intermediate portion of the workpiece 14. The stretching forces applied to the ends of the workpiece by the gripping units 23, cause the end portions of the workpiece to be drawn downwardly and around the curved side portions 15^b of the die punch. During this stretching and bending of the end portions of the workpiece around the curved side portions of the die punch, the rocker members 22 are swung relative to the die punch by the power cylinder devices 27 and 28 and are also shifted toward or away from the die punch by movement imparted to the slide means 24 by the power cylinder devices 25 and 26. The gripping units 23 swing in the rocker members 22 during the rocking and translatory movements of the latter, such that the resultant movement of the gripping units causes them to assume substantially upright positions adjacent the curved side portions 15^b of the die punch with the grip heads 24 pointing in a generally upward direction.

From the foregoing description and the accompanying drawings, it will now be readily understood that this invention provides a novel stretch bending machine in which the work gripping units are carried by slide means provided on the main carriages and in which alignment control means interconnecting the slide means with the carriages, confines the slide means for a desired parallel translatory movement which effectively prevents skewing or misalignment. It will, likewise, be understood that the slide mounting for the gripping units provides for a more rapid and satisfactory movement of the gripping units for engaging the same with, or disengaging the same from, the successive workpiece.

Although the novel stretch bending machine

has been illustrated and described herein to a somewhat detailed extent, it will be understood, of course, that the invention is not to be regarded as being limited correspondingly in scope, but includes all changes and modifications coming within the terms of the claims hereof.

Having thus described my invention, I claim:

1. In stretch bending apparatus, a frame having a longitudinal guideway, a carriage movable along said guideway, actuating mechanism operable to move said carriage along said longitudinal guideway, means defining a pair of transversely spaced second guideways on said carriage, slide means comprising block members movable along said second guideways and a transversely extending rotatable shaft journaled in said block members, actuating means operable to move said slide means along said second guideways, a work gripping device engageable with a workpiece, and rocker means carrying said gripping device and supported by said shaft for rocking movement about the axis of the latter.

2. In stretch bending apparatus, a frame having a longitudinal guideway, a carriage movable along said guideway, actuating mechanism operable to move said carriage along said longitudinal guideway, means defining a pair of transversely spaced second guideways on said carriage, slide means comprising block members movable along said second guideways and a transversely extending rotatable shaft journaled in said block members, actuating means operable to move said slide means along said second guideways, a work gripping device engageable with a workpiece, and rocker means carrying said gripping device and journaled for rocking movement on said shaft between said block members.

3. In stretch bending apparatus, a frame having a longitudinal guideway, a carriage movable along said guideway, actuating mechanism operable to move said carriage along said longitudinal guideway, means defining a pair of transversely spaced second guideways on said carriage, slide means comprising block members movable along said second guideways and a transversely extending rotatable shaft journaled in said block members, rocker means mounted on said shaft between said block members and rockable about the axis of said shaft, actuating means operable to move said slide means along said second guideways, power cylinder means mounted on said carriage and connected with said rocker means for imparting rocking movement to the latter, a work gripping unit, means pivotally mounting said gripping unit on said rocker means for swinging movement relative to the latter, racks on said carriage adjacent said second guideways, and pinions fixed on said shaft and meshing with said racks.

4. Stretch bending apparatus as defined in claim 3 in which said rocker means comprises a pair of side members spaced apart axially of said shaft, and in which said work gripping unit is swingable in the space between said side members.

5. Stretch bending apparatus as defined in claim 4 in which said power cylinder means comprises a pair of cylinder devices spaced apart axially of said shaft and having the cylinders thereof pivotally connected with said carriage, and in which said cylinder devices have piston rods connected with said side members.

6. In a stretch bending machine of the type having a movable die punch engageable with an intermediate portion of a workpiece and gripping

devices engageable with the ends of the workpiece and located on opposite sides of said die punch, a main frame having a first guideway extending in a direction away from said die punch, a carriage movable along said first guideway and having laterally spaced upright longitudinal side members thereon provided with longitudinal slots defining a second guideway extending in a direction away from said die punch, slide means movable along said second guideway and forming a movable carrier for one of said gripping devices and including blocks slideable in said slots, actuating mechanism operable to move said carriage along said first guideway, actuating mechanism operable to move said slide means along said second guideway, a shaft extending transversely of said carriage and rotatably mounted in said blocks, and pairs of cooperating gear elements of the rack and pinion type spaced apart transversely of said carriage, the racks of the paired gear elements being attached to said side members adjacent said slots and the pinions being fixed on said shaft.

7. In a stretch bending machine of the type having a movable die punch engageable with an intermediate portion of a workpiece and gripping devices engageable with the workpiece and located on opposite sides of said die punch, a main frame having a first guideway extending in a direction away from said die punch, a carriage movable along said first guideway and itself having a second guideway extending in a direction away from said die punch, slide means movable along said second guideway, actuating mechanism operable to move said carriage along said first guideway, actuating mechanism operable to move said slide means along said second guideway, a transversely extending shaft rotatably mounted in said slide means, pairs of cooperating gear elements of the rack and pinion type spaced apart transversely of said carriage, the racks of the paired gear elements being attached to said carriage and the pinions being fixed on said shaft, and rocker means rockable on said shaft and having one of said gripping devices mounted thereon.

8. In a stretch bending machine, a movable die punch engageable with an intermediate portion of a workpiece extending thereacross, an elongated frame including substantially longitudinally aligned end frame members extending away from said die punch and located on opposite sides thereof, first guideways on said end frame members and extending longitudinally thereof, carriages movable along the guideways of said end frame members, actuating means operable to cause such movement of said carriages, second guideways on said carriages and extending in substantially the same direction as said first guideways, slide units movable along said second guideways, rocker units carried by said slide units and being rockable thereon toward and away from said die punch, gripping units swingably carried by said rocker units and adapted for gripping engagement with end portions of said workpiece, actuating devices operable to cause movement of said slide units along said second guideways, and alignment control gearing interconnecting said slide units with their respective carriages and confining said slide units to substantially parallel translatory movement along said second guideways.

9. In a stretch bending machine, a movable die punch engageable with an intermediate portion of a workpiece extending thereacross, an

elongated frame including substantially longitudinally aligned end frame members extending away from said die punch and located on opposite sides thereof, first guideways on said end frame members and extending longitudinally thereof, carriages movable along the guideways of said end frame members, actuating means operable to cause such movement of said carriages, laterally spaced upright longitudinal side members on said carriages and provided with longitudinal slots defining pairs of second guideways on said carriages and spaced apart transversely thereof, slide units on said carriages and each comprising a pair of block members slideable in a pair of said slots and a transversely extending shaft journaled in said pair of block members, gripping units carried by said slide units and adapted for gripping engagement with end portions of said workpiece, pairs of power cylinder devices on said carriages and connected with said block members and being operable to cause movement of said slide units along said second guideways, pairs of racks on said carriages adjacent the slots thereof, and pinions fixed on the shafts of said slide units and meshing with said pairs of racks.

10. In a stretch bending machine, a movable die punch engageable with an intermediate portion of a workpiece extending thereacross, an elongated frame including substantially longitudinally aligned end frame members extending away from said die punch and located on opposite sides thereof, first guideways on said end frame members and extending longitudinally thereof, carriages movable along the guideways of said end frame members, actuating means operable to cause such movement of said carriages, pairs of second guideways on said carriages and spaced apart transversely thereof, slide units on said carriages and each comprising a pair of block members slideable in a pair of said second guideways and a transversely extending shaft journaled in said pair of block members, rocker units swingably mounted on the shafts of said slide units between the pairs of said block members, gripping units carried by said rocker units and adapted for gripping engagement with end portions of said workpiece, transversely spaced power cylinder devices on said carriages and operably connected with said block members for causing movement of said slide units along said second guideways, pair of racks on said carriages adjacent the second guideways thereof, and pinions fixed on said shafts and meshing with said pairs of racks.

11. In a stretch bending machine, a movable die punch engageable with an intermediate portion of a workpiece extending thereacross, an elongated frame including substantially longitudinally aligned end frame members extending away from said die punch and located on opposite sides thereof, first guideways on said end frame members and extending longitudinally thereof, carriages movable along the guideways of said end frame members, actuating means operable to cause such movement of said carriages, pairs of second guideways on said carriages and spaced apart transversely thereof, slide units on said carriages and each comprising a pair of block members slideable in a pair of said second guideways and a transversely extending shaft journaled in said pair of block members, rocker units swingably mounted on the shafts of said slide units between the pairs of said block members, gripping units carried by said rocker units

and adapted for gripping engagement with end portions of said workpiece, transversely spaced power cylinder devices of said carriages and operably connected with said block members for causing movement of said slide units along said second guideways, pairs of racks on said carriages adjacent the second guideways thereof, pinions fixed on said shafts and meshing with said pairs of racks, and power cylinder devices mounted on said carriages and operably connected with said rocker units for imparting swinging movement thereto.

12. A stretch bending machine as defined in claim 10 in which said rocker units comprise side members spaced apart axially of said shafts, and in which said gripping devices are pivotally mounted on the respective rocker units for

swinging movement between the side members of the latter.
